Patented Sept. 5, 1916.

UNITED STATES PATENT OFFICE.

ANDRÉ E. BLONDEL, OF PARIS, FRANCE.

PHOTOGRAPHIC RECORDER.

1,196,837.

Specification of Letters Patent. Patented Sept. 5, 1916.

Application filed August 5, 1913, Serial No. 783,208. Renewed July 27, 1916. Serial No. 111,750.

To all whom it may concern:

Be it known that I, ANDRÉ E. BLONDEL, a citizen of the Republic of France, residing at Paris, France, have invented new and useful Photographic Recorders; and I do hereby declare the following to be a full, clear, and exact description of the same.

In French specification No. 419118 are described various improvements for photographic recording of galvanometers with quick vibrations or of other instruments with mirrors, for the purpose of increasing the light projected on the photographic screen, and convenience and speed of recording.

In order to obtain the greatest possible amount of light, the distance between the mirrors of the galvanometers, and the photographic emulsion, is reduced, which results in a reduction of the sensitiveness of deflection.

In order to obviate the disadvantage in question, the following principle has been suggested which consists in causing the recording apparatus to operate automatically mechanical or electric relays which short-circuit, only during the recording of the curves, shunts placed between the terminals of the galvanometers. Owing to the use of these shunts, it is possible to send permanently into the galvanometers only currents sufficiently weak for not heating the galvanometers. By suddenly cutting off these shunts, it is possible to double or treble or to increase in any desired proportion, in accordance with the foregoing system of shunts, the current temporarily passing through the galvanometers. This makes it possible therefore to increase to a considerable extent the deflections even with an optical system of small length.

The same contact can be used for short-circuiting a portion of the resistance which feeds the arc lamp lighting the galvanometers, and in that way for increasing also for a moment, during the time of recording the strength of illumination. On the other hand, in order to enable zero lines for each curve to be traced, a cut-out relay controlled by electric contacts closed by the photographic recorder, either at the beginning or at the end, or preferably at the beginning and at the end of each record of curves, is placed in series with each movable device of the

galvanometers. These cut-out relays must give a very good contact when the oscillograph is connected up for low pressure, and in such case it is preferable to use mercury cut-outs controlled by an electro-magnet.

These automatic devices described can be carried out in various ways and do not present any difficulty for any engineer used to employing relays.

Figure 1 shows, by way of example, a dia-grammatic view of one form of the invention; Figs. 2, 3 and 4 show dia-grammatic views of portions of several modifications.

Having fully described my invention, what I claim and desire to secure by Letters Patent is:—

1. A photographic recording process, consisting in controlling a mirror by an instrument the movements of which are to be recorded, sending a beam of light into said mirror, transmitting said beam onto a moving light sensitive surface, and increasing or decreasing the sensitiveness of the records during the displacement of the sensitive surface.

2. In a photographic recorder, the combination with the source of electric light, of a mirror controlled by the instrument the movements of which are to be recorded, a light sensitive surface adapted to receive a beam of light, relays acting on the circuit of the source of light and relays acting on the instrument, whereby the sensitiveness of the instrument may be increased or reduced.

3. In a photographic recorder, the combination of a source of electric light, of a mirror controlled by the instrument the movements of which are to be recorded, a system of cylindrical lenses having the axes of their cylindrical surfaces vertical, a light-sensitive surface adapted to receive a beam of light deflected by the movements of said mirror, relays acting on the circuit of the source of light and relays acting on the instrument, whereby the sensitiveness of the instrument may be increased or reduced.

4. In a photographic recorder, the combination of a source of electric light, of a mirror controlled by the instrument the movements of which are to be recorded, a system of cylindrical lenses having the axes of their cylindrical surfaces vertical, a light-sensitive surface adapted to receive a beam of light deflected by the movements of said mirror, electric contacts opened and closed

by said moving surface, and a cut-out relay controlled thereby and opening and closing the circuit of the instrument.

5. In a photographic recorder, the combination of a source of electric light, of a mirror controlled by the instrument the movements of which are to be recorded, a system of cylindrical lenses having the axes of their cylindrical surfaces vertical, a light-sensitive surface adapted to receive a beam of light deflected by the movements of said mirror, electric contacts opened and closed by said moving surface, a cut-out relay controlled thereby and opening and closing 10 the circuit of the instrument, and cut-out relays acting on the circuit of the source of light.

6. In a photographic recorder, the combination of a mirror galvanometer; an arc-lamp; a movable plate holder for carrying a sensitive plate; a system of lenses for directing the light of the lamp upon the mirror and concentrating it on said plate; a battery having one pole electrically connected to the holder; a cut-out relay; a pair of contacts adapted to contact the plate only at the limits of its movement; a conductor connected to said contacts passing around the magnet of the relay to the other pole of the battery; and a circuit adapted to connect in series the apparatus to be tested, and to be broken by said relay.

7. In a photographic recorder, the com-

bination of a mirror galvanometer; an arc-lamp; a movable plate holder for carrying a sensitive plate; a system of lenses for directing the light of the lamp upon the mirror and concentrating it on said plate; a battery having one pole electrically connected to the holder; a cut-out relay; a pair of contacts adapted to contact the plate only at the limits of its movement; a conductor connected to said contacts passing around the magnet of the relay to the other pole of the battery; a circuit adapted to connect in series the apparatus to be tested, and to be broken by said relay; a contact adapted to contact with the holder only during the movement of the holder; a conductor connected to said last named contact and connected to the pole of the battery to which said flexible conductor is not connected; relays in said conductor; a shunt around the galvanometer and adapted to be cut by one of said last named relays; and a resistance in series with the arc-lamps and adapted to be short-circuited by the other of said last named relays.

In testimony whereof, I have signed my name to this specification in the presence of two subscribing witnesses.

ANDRÉ E. BLONDEL.
